GARMENT BLOCKER

**Kenneth R. Larson, Des Plaines, and John G. Bilz,
Niles, Ill., assignors to Carl B. Albert, Milwaukee,
Wis.**

Application February 23, 1946, Serial No. 649,486

18 Claims. (Cl. 223—69)

1

This invention relates to adjustable frames such as garment blockers and more particularly to improved adjustable locking devices therefor, although it and certain features thereof may be employed with equal advantage for other purposes.

It contemplates more especially the provision of improved adjustable frame guide and fastener means for rendering such adjustable and maintaining the elements thereof in any adjusted relation within their intended size range or limit.

Adjustable frames usually embody overlapping wires and this is true of blockers or driers for garments which are normally of varied style and size to conform with the dimensional and shape characteristics of different individuals. In order to effectively block various sized garments of knit construction, it is highly desirable to have the blocker adjustable to different shapes and sizes as well as positional support, thereby requiring the component elements thereof including the sleeves to be readily adjustable and easily maintained in adjusted relation to meet the problems incident to drying display and fittings.

Most garments vary in contour as well as shoulder and hip characteristics in the same sizes to the end that it is almost impossible to properly block every possible knit garment within the same general size dimensions. In order to overcome this serious defect of ordinary garment blockers as well as to preclude the necessity of stocking numerous types of garment blocking devices, it is proposed to provide adjustment features to conform with specifically shaped and sized garments in order to support, dry, shape or block such in an expeditious manner.

Numerous types of adjustable frames such as garment blockers have heretofore been proposed, but the adjustable retaining means on these have either been too expensive or are not entirely satisfactory from a production and operation standpoint owing to the inability to render such quickly adjustable without entailing any appreciable manipulation, difficulty and production expense. Most locking expedients are either structurally intricate or expensive in production or will not satisfactorily operate unless produced and assembled within precision tolerances or for that matter involve moving parts which do not always function satisfactorily for use with garments of greatly varying size. Further, considerable difficulty is encountered in maintaining the component elements thereof in adjusted relation without the adjusting or locking means serving as an obstruction to the garment.

2

It must be appreciated that in the use of garment blockers, such necessarily are subjected to the wet garments so that the component elements thereof must be readily associative and removable relative to the garment without obstruction. It is also desirable that the component elements and the expedients for maintaining such in adjusted relation should not become involved with the material of which the garment is made nor should such protrude to any extent to avoid impairment to the garment. This is particularly true of the sleeves which usually are attached to frame eyelets that interrupt smoothness of garment contour and obstruct the garment in the association thereof with the frame, especially when the arm forms are not utilized which occurs often owing to the judgment of the user and the requirements of the garment.

With the teachings of the present invention, the adjustable retaining means are shaped from the frame wire to comprise an integral portion thereof. The arm forms have their own integral retainers for frictional adjustable grasp of the smooth frame wire to render such readily attachable and detachable relative to the frame body, easily adjustable in size, and inexpensive in construction.

One object of the present invention is to provide improved adjustable locking means for blockers to conform with various sized and styled garments.

Another object is to provide improved, more simple and less expensive adjusting expedients for garment blockers having shoulder and/or waist and/or skirt portions readily adjustable to meet different styled and sized garment characteristics.

Still another object is to provide improved and less expensive frame guiding and locking expedients integrally shaped from frame portions to afford effective blocker adjustments to accommodate varied garments for expeditious garment blocking.

A further object is to provide novel wire guiding and locking means integral with garment blocker frames for maintaining such in adjusted size without the locking means serving as an appreciable obstruction to the garment.

A still further object is to provide improved, dependable, and simple combination overlapping frame wire guiding and locking means shaped from the frame body for maintaining garment blockers and their appendages in adjusted position to effectively stretch and maintain various sizes in clothes during the drying thereof.

Still another object is to provide an improved adjustable frame and arm guiding and locking means that do not embody movable parts for maintaining garment blockers in adjustment and afford instant adjustment and convenient manipulation responsive to a relative displacing urge on the frame elements.

Other objects and advantages will appear from the following description of an illustrative embodiment of the present invention.

In the drawings:

Figure 1 is a front view in elevation of a garment blocker having improved adjusting fasteners embodying features of the present invention.

Figure 2 is an enlarged fragmentary top edge view of the left-hand spring guiding clip shown in conjunction with the bottom blocker edge as illustrated in Figure 1.

Figure 3 is an enlarged fragmentary front view in elevation of the spring guiding clip shown in Figure 2.

Figure 4 is an enlarged fragmentary top edge view of the right-hand spring guiding clip shown in conjunction with the bottom blocker edge as illustrated in Figure 1.

Figure 5 is an enlarged fragmentary front view in elevation of the spring guiding clip shown in Figure 4.

Figure 6 is a front view in elevation of a modified blocker wherein the bottom frame overlapping portions are provided with modified guiding and retaining elements.

Figure 7 is an enlarged fragmentary view in elevation of the modified resilient adjusting and retaining means provided on the bottom overlapping frame portions as illustrated in Figure 6.

Figure 8 is a bottom edge or plan view of the lower portion of the modified garment frame shown in Figures 6 and 7.

Figure 9 is an enlarged front view in elevation of the frame grasping resilient clip at the upper terminus of the sleeve form.

Figure 10 is a left end view of the resilient sleeve clips shown in Figure 9.

Figure 11 is a bottom edge or plan view of the clip shown in Figures 9 and 10.

Figure 12 is an enlarged fragmentary front view in elevation of the resilient spring clip constituting the lower terminus of the sleeve form.

Figure 13 is a top plan view of the resilient spring clip shown in Figure 12.

Figure 14 is a left edge or side view of the resilient spring clip shown in Figure 12.

The structure selected for illustration is not intended to serve as a limitation upon the scope or teachings of the invention, but is merely illustrative thereof. There may be considerable variations and adaptations of all or part of the teachings depending upon the dictates of commercial practice. The present embodiment comprises any suitable adjustable frame 10 consisting of a plurality of sections such as 11 and 12, in this instance two, preferably though not essentially bent or otherwise shaped from wire to provide overlapping portions or elements 13-14 and 15-16, although intermediate overlapping wire elements may be provided should commercial practice so dictate. The frame sections 11-12 define, in this instance, an adjustable sweater garment blocker, although the particular configuration thereof may be varied within a wide range depending upon the dictates of commercial practice.

So that the frame sections 11-12 may be adjustable in size responsive to guided displace-

ment of the overlapping wire frame portions 13-14 and 15-16 relative to each other and to slidably confine them for relative extensible adjustment, each of the overlapping wire frame portions 13-14 and 15-16 have, in this instance, combined guiding and frictional retaining fasteners anchored to each or preferably bent or articulated therefrom for yielding contact with their adjacent overlapping frame wire portions 13-14 and 15-16 and vice versa to maintain the frame sections 11-12 in any desired extensible relation to determine the size thereof within their limit of adjustment. To this end, the combined guiding and retaining elements preferably comprise integral spring clips 17-18 and 19-20 bent or otherwise shaped from the extremities of the overlapping wire frame portions 13-14 and 15-16, respectively.

The spring clips 17-20 and 18-19 are identical in shape, structure and functional characteristics so that the description of each set will suffice and avoid repetition in that these sets are inverted and oppositely disposed to serve the same function on their respective overlapping wire portions 13-14 and 15-16. The resilient spring clips 18-19 each comprise a double convolution 21 defining, in this instance, a circular spring loop or coil 22 which extends integrally from the overlapping wire portion 14 or 16 to terminate in an inclined leg 23 converging with the overlapping wire frame portion 14 or 16.

The converging coil leg 23 terminates in a transversely disposed ring or eyelet 24 formed integral therewith to envelop the superposed overlapping wire frame portions 13-14 or 15-16. The eyelet 24 on each clip 18 and 19 is integral with the overlapping frame portions 14 and 16, respectively to serve as a guide for the other confronting overlapping frame portions 13 and 15, respectively. The resilient spring clips 18 and 19 with their eyelets 24 are illustrative of means associated with each of said garment form overlapping portions 14 and 16 to slidably guide and resiliently retain the other of said garment form overlapping and confronting portion 13 and 15, respectively, in adjusted overlapping extensible relation relative thereto or in other words relative to each other. Thus the spring clips 17-20 and 18-19 serve to retain the frame sections 11-12 in free slidable relation responsive to exerting an opposite pushing or pulling force on the overlapping wire members 13-14 or 15-16.

The eyelet or ring 24 has its terminus 25 proximate to or abutting against the extremity of the converging coil leg 23 as a transverse offset thereof to define the slidable guide and retaining eyelet or ring 24. It should be noted that the angularity of the converging leg 23 as it emerges from the convoluted spring coil 22, exerts an urge 60 upon the eyelet or ring 24 in a direction transverse to the overlapping frame wire portions 13-14 or 15-16 to establish frictional contact therewith. The friction contact established by the eyelet or ring member 24 responsive to the transverse spring urge exerted by the coil 22, is sufficient to retain the slidable overlapping wire frame portions 13-14 or 15-16 in their adjusted relation without precluding any accidental relative sliding displacement therebetween.

The other spring clip 20 on the opposite end of the overlapping frame wire portions 13-14 and 15-16, is similarly shaped to form a spring coil 26 which emerges from an arcuately connecting portion 27 extending from the straight 75 overlapping frame wire portion 13 or 15. This

brings the spring coil 26 in alignment with the superposed adjacent wires 13-14 or 15-16 to provide an inclined leg 28 that converges with the overlapping wire members 13-14 or 15-16 at a point substantially in confronting relation with the contacting edge of the superposed wires 15-16. The converging leg 28 has a short horizontal arm 29 in parallel contact alignment with the overlapping frame wire portion 13 or 15 to terminate in an eyelet or ring member 30 that envelops the superposed wire frame members 13-14 or 15-16.

The ring or eyelet 30 has a terminus 31 which is disposed proximate to or contacts with the starting point of the eyelet or ring member 30 to maintain the overlapping frame wire members 13-14 and 15-16 in slidably superposed alignment. Similarly to the coil 22, the coil 26 exerts a transverse displacing influence on the eyelet or ring member 30 to frictionally maintain the adjacent overlapping frame wire portions 13-14 and 15-16 in frictional contact. As a result, the frame sections 11-12 can be relatively displaced to decrease or increase the size thereof as illustrated in dotted outline in Figure 1. This is accomplished by merely grasping the spring coils 22-26 of the spring clips 17-18 and/or 19-20 with the thumb and finger of each hand and moving them toward or away from each other to respectively enlarge or decrease the size of the frame 10 to conform with a knitted sweater or other garment for drying thereon.

The usual garment such as a sweater has arms which should be shaped during the blocking or drying thereof, and this is accomplished by providing substantially U-shaped wire sleeve forms 32-33 which have their converging side legs 34-35 terminate at their free extremities in spring clips 36 and 37 to frictionally grasp the frame 10 in the region of the arm pit regions thereof. The arm pit regions 38-39 of the frame 10 have arcuate portions of different curvature and inclination to the end that the upper and lower sleeve form clips 36-37 are somewhat differently disposed as is apparent in Figures 10 to 14 inclusive. As shown, the upper sleeve form clips 36 (Figure 9) have a straight leg 38' constituting an extension of the upper sleeve form arm 34.

The leg 38' terminates in a depending substantially semi-circular arm 39' which is reversely bent to provide a diagonal leg 40 terminating substantially in alignment with and spaced from the starting point 41 of the semi-circular arm 39'. However, the terminus 42 of the reversely extending and diagonal leg 40 need not be exactly in line with the starting point 41 of the semi-circular arm 39' in that this may vary within a wide range to merge in another semi-circular arm or convolution 43. The semi-circular arm or convolution 43 depends from the diagonal leg 40 in spaced parallel relation with the semi-circular arm or convolution 39' for a distance somewhat less than the diameter of the wire from which the frame 10 is articulated for frictional grasping reception therein. The spaced and somewhat smaller semi-circular arm or convolution 43 terminates in an inclined leg 44 which converges with the leg 39' in an offset clip extremity 45 to abut against the sleeve form leg 34 for anchored association therewith in any suitable manner such as welding along their meeting edge as at 46 to rigidly anchor the spaced parallel arms or convolutions 39'-43 serving as a spaced spring coil.

The offset clip extremity 45 preferably has a

tapered edge 47 to minimize or eliminate any obstruction with the garment sleeve disposed over the sleeve forms 32 and 33. The terminal confronting surface of the semi-circular arms 39'-43 are bowed or depressed as at 48-49 to provide aligned retaining seats for the frame 10 that is frictionally clinched therebetween for attachment and detachment of as well as slidable connection to the upper legs 34 of the sleeve form 32-33. It should be noted that the spaced confronting clip arms 39'-43 constitute a spring coil wherein the spaced arms 39'-43 serve as spaced convolutions thereof to frictionally and slidably grasp a rigid member such as the frame 10 therebetween.

The lower legs 35 of the sleeve form 32-33 are provided with a spring clip 37 shaped similarly to the spring clip 36 described supra and formed on the upper leg 34 of the same sleeve forms 32-33. However, the lower sleeve form clip 37 is oppositely disposed and inclined at a different angle to conform substantially with the inclination of the wire in the lower portion of the arm pit regions 38-39 of the adjustable frame 10 so that the latter is resiliently clinched therewith to support the terminal ends 36-37 of each of the sleeve forms 32-33. This construction also enables the sleeve forms 32-33 to be enlarged or decreased in spread as shown in dotted outline in Figure 1 to conform with the desired arm measurements of a knit sweater or other garment disposed thereover. The sleeve forms 32-33 are identical in construction and, in fact, they may be interchangeably used in connection with either arm pit 38-39 of the frame 10.

It should be noted that the garments such as knit sweaters are first placed on the frame 10 with the sleeve forms 32-33 detached therefrom. Thereafter, the sleeve forms 32-33 are inserted through the neck or open bottom of the sweater for displacement into the sleeves thereof. Thereupon, the sleeve forms 32-33 are attached to the arm pit regions 38-39 of the frame 10 to assume the desired proportions by adjustment therewith for filling the garment sleeves which are blocked or permitted to dry thereon after washing.

In the modified embodiment shown in Figures 6 and 7, the frame 10' is provided with the upper frame overlapping portions 13'-14' having the adjustable guiding and retaining elements 17'-18' illustrated and described in Figure 1. However, the bottom frame overlapping portions 15'-16' are provided with modified resilient guide and spring clips 19'-20' comprising an adaptation of the spring clips 36-37 constituting the attaching and detaching expedients for the sleeve forms 32-33 illustrated and described in the embodiment shown in Figures 1 and 9 to 14 inclusive. The overlapping frame portions 15'-16' terminate at their free extremities in the spring clips 19'-20' that integrally extend therefrom and are shaped to conform substantially in configuration and structure with the spring clips 36 and 37 illustrated in Figures 9 and 12, respectively. The clip 19' is exactly the same as the clip 36 of Figure 9 except that it is bent upwardly with the end of the spaced convolution 43' spot-welded directly to the wire 15' as at 44' to provide spaced convolutions 39''-43' to frictionally receive the adjacent sliding frame overlapping portion 16' therebetween. In this instance, the spaced arms or convolutions 39''-43' of the spring clip or coil 19' are somewhat more elongated in the transverse di-

rection relative to the frame overlapping portions 15'-16' to accommodate and slidably retain the adjacent overlapping frame portion 16'-15'. In this case, the diagonal arm connecting leg 40' is positioned somewhat beyond the frame overlapping wire portion 15' to provide the proper resiliency for the grasping of the adjacent frame overlapping wire portion 16' and vice versa.

The spring coils or clips 19'-20' are provided with confronting pairs of aligned indentations 48'-49' to serve as seats for the frame overlapping portions 16' frictionally disposed between the spaced convolutions 39'-43'. The spring clip or coil 20' is similarly constructed to integrally extend from the frame overlapping wire portion 16' to frictionally grasp the adjacent relatively slidably frame overlapping portion 15' for the adjusted retention thereof in its desired relative position. Thus, the spring clip or coil 20' is identical in construction to the spring clip or coil 19', except that the spring clips or coils 19'-20' extend oppositely to render the frame overlapping wire portion 15'-16' extensible in either direction (Figures 6, 7 and 8). The spring clips 19'-20' may also be utilized to resiliently grasp and retain the upper frame overlapping wire portions 13'-14' in lieu of the spring clips 17'-18' depending upon the dictates of commercial practice.

It should be noted that the modified sleeve forms 32'-33' may be provided to conform with the short sleeve shapes of slip-over sweaters worn by junior sized individuals. The sleeve forms 32'-33' are of the "bobby" type; however, their frictional or resilient clips 36'-37' are identical in structure with those shown on the conventional sleeve form 32-33. The modified sleeve forms 32'-33' are shown in dotted outline in Figure 1 while the conventional sleeve form 32 is shown in dotted outline on the modified embodiment shown in Figure 6. These fully detachable sleeve forms 32'-33' are especially advantageous in that no obstructing expedients need be attached to the frame 10 or 10' so that these frames may be utilized for blocking or drying sweaters in instances where the individual is not desirous of using the sleeve forms 32-33 and/or 32'-33'.

While we have illustrated and described a preferred embodiment of this invention, it must be understood that the invention is capable of considerable variation and modification without departing from the spirit of the invention. We, therefore, do not wish to be limited to the precise details of construction set forth, but desire to avail ourselves of such variations and modifications as come within the scope of the appended claims.

We claim:

1. In a device of the character described, the combination with a garment form having relatively slidable overlapping portions for defining adjustable interior shapes of garments to be sized thereon, and pre-set non-adjustable friction clutching means associated with each of said garment form overlapping portions to slidably guide and resiliently retain the other of said garment form overlapping portions in adjusted overlapping extensible relation relative thereto to support variously sized and shaped garments on said form, said friction clutching means being effective to permit relative sliding of said overlapping frame portions responsive to exerting relative sliding displacement thereof to manually change the frame size and to retain said overlapping frame portions against relative slidable displacement responsive to the force exerted by the garment thereon, whereby frame size adjustment may be effected without manipulation of said friction clutching means.

2. In a device of the character described, the combination with a garment form having relatively slidable overlapping portions for defining adjustable interior shapes of garments to be sized thereon, and spring mounted friction clutching guide ring means integrally extending from each of said garment form overlapping portions to slidably guide and resiliently retain the other of said garment form overlapping portions in adjusted overlapping extensible relation relative thereto to support variously sized and shaped garments on said form.

3. In a device of the character described, the combination with a garment form having relatively slidable overlapping portions for defining adjustable interior shapes of garments to be sized thereon, and coil spring suspended friction clutching guide ring means associated with each of said garment form overlapping portions to slidably guide and resiliently retain the other of said garment form overlapping portions in adjusted overlapping extensible relation relative thereto to support variously sized and shaped garments on said form.

4. In a device of the character described, the combination with a wire garment form having relatively slidable overlapping portions for defining adjustable interior shapes of garments to be sized thereon, and wire spring clip pre-set non-adjustable friction clutching means bent from each of said garment form overlapping portions to slidably guide and resiliently retain the other of said garment form overlapping portions in extensible relation relative thereto to support variously sized and shaped garments on said form, said friction clutching means being effective to permit relative sliding of said overlapping frame portions responsive to exerting relative sliding displacement thereof to manually change the frame size and to retain said overlapping frame portions against relative slidable displacement responsive to the force exerted by the garment thereon, whereby frame size adjustment may be effected without manipulation of said friction clutching means.

5. In a device of the character described, the combination with a wire garment form having relatively slidable overlapping portions for defining adjustable interior shapes of garments to be sized thereon, and pre-set non-adjustable friction clutching means bent from each of said garment form overlapping portions in enveloping relation therewith to slidably guide and resiliently retain the other of said garment form overlapping portions in adjusted overlapping extensible relation relative thereto to support variously sized and shaped garments on said form, said friction clutching means being effective to permit relative sliding of said overlapping frame portions responsive to exerting relative sliding displacement thereof to manually change the frame size and to retain said overlapping frame portions against relative slidable displacement responsive to the force exerted by the garment thereon, whereby frame size adjustment may be effected without manipulation of said friction clutching means.

6. In a device of the character described, the combination with a wire garment form having

relatively slidable overlapping portions for defining adjustable interior shapes of garments to be sized thereon, and wire spring clip pre-set non-adjustable friction clutching means including a convoluted spring member bent from each of said garment form overlapping portions to slidably guide and resiliently retain the other of said garment form overlapping portions in adjusted overlapping extensible relation relative thereto to support variously sized and shaped garments on said form, said friction clutching means being effective to permit relative sliding of said overlapping frame portions responsive to exerting relative sliding displacement thereof to manually change the frame size and to retain said overlapping frame portions against relative slidable displacement responsive to the force exerted by the garment thereon, whereby frame size adjustment may be effected without manipulation of said friction clutching means.

7. In a device of the character described, the combination with a wire garment form having relatively slidable overlapping portions for defining adjustable interior shapes of garments to be sized thereon, and pre-set non-adjustable friction clutching means including a spring mounted guide member bent from each of said garment form overlapping portions in enveloping relation therewith to slidably guide and resiliently retain the other of said garment form overlapping portions in adjusted overlapping extensible relation relative thereto to support variously sized and shaped garments on said form, said friction clutching means being effective to permit relative sliding of said overlapping frame portions responsive to exerting relative sliding displacement thereof to manually change the frame size and to retain said overlapping frame portions against relative slidable displacement responsive to the force exerted by the garment thereon, whereby frame size adjustment may be effected without manipulation of said friction clutching means.

8. In a device of the character described, the combination with a wire garment form having relatively slidable overlapping portions for defining adjustable interior shapes of garments to be sized thereon, and wire spring loop and connecting guide ring friction clutching means bent from each of said garment form overlapping portions to slidably guide and frictionally retain the other of said garment form overlapping portions in adjusted overlapping extensible relation relative thereto to support variously sized and shaped garments on said form.

9. In a device of the character described, the combination with a wire garment form having relatively slidable overlapping portions for defining adjustable interior shapes of garments to be sized thereon, and wire spring loop and connecting guide ring friction clutching means bent from each of said garment form overlapping portions in offset spaced enveloping relation therewith to slidably guide and frictionally retain the other of said garment form overlapping portions in adjusted overlapping extensible relation relative thereto to support variously sized and shaped garments on said form.

10. In a device of the character described, the combination with a wire garment form having relatively slidable overlapping portions for defining adjustable interior shapes of garments to be sized thereon, and wire spring loop and connecting guide ring means bent from each of said garment form overlapping portions in offset

spaced enveloping relation therewith, said guide ring means extending transversely around said garment form overlapping portions and connected by an angular leg with said wire spring loop to slidably guide and frictionally retain the other of said garment form overlapping portions in adjusted overlapping extensible relation relative thereto to support variously sized and shaped garments on said form.

11. A form appendage element comprising a preformed member and a confronting rigid member, and confronting resilient pre-set non-adjustable friction clutching ends extending from said preformed member to frictionally grasp said confronting rigid member therebetween anywhere along the length thereof to slidably guide and retain said members in adjusted relation, said confronting resilient arms being effective to permit relative sliding of said preformed member relative to said rigid member responsive to exerting relative sliding displacement thereof to manually change their relative position and to retain said members against relative slidable displacement responsive to the force exerted by the garment thereon whereby their relative adjusted relation may be changed without manipulation of said confronting resilient arms.

12. A form appendage element comprising a preformed member and a confronting rigid member, and confronting interconnected resilient pre-set non-adjustable friction clutching ends extending from said preformed member to frictionally and slidably grasp said confronting rigid member therebetween anywhere along the length thereof to slidably guide and retain said members in adjusted relation, said confronting resilient arms being effective to permit relative sliding of said preformed member relative to said rigid member responsive to exerting relative sliding displacement thereof to manually change their relative position and to retain said members against relative slidable displacement responsive to the force exerted by the garment thereon whereby their relative adjusted relation may be changed without manipulation of said confronting resilient arms.

13. A form appendage element comprising a preformed member and a confronting rigid member, and confronting interconnected resilient spaced coil convolutions extending from said preformed member to frictionally and slidably grasp said confronting rigid member therebetween anywhere along the length thereof to slidably guide and retain said members in adjusted relation.

14. A form appendage element comprising a preformed member and a confronting rigid member, confronting interconnected resilient spaced coil convolutions extending from said preformed member, and means for anchoring the last spaced coil convolution to said preformed member to frictionally and slidably grasp said confronting rigid member therebetween anywhere along the length thereof to slidably guide and retain said members in adjusted relation.

15. In a device of the character described, the combination with a garment form having relatively slidable overlapping portions for defining adjustable interior shapes of garments to be sized thereon, and resiliently spaced convolutions defining dual guide and retaining clips associated with the free ends of said garment form overlapping portions to slidably guide and resiliently retain the other of said garment form overlapping portions in adjusted extensible rela-

tion to support variously sized and shaped garments on said form.

16. In a device of the character described, the combination with a garment form having relatively slidable overlapping portions for defining adjustable interior shapes of garments to be sized thereon, resiliently spaced convolutions defining dual guide and retaining clips associated with the free ends of said garment form overlapping portions, and means for anchoring each of said spaced clip convolutions to said garment form overlapping portions to slidably guide and resiliently retain the other of said garment form overlapping portions in adjusted extensible relation therewith to support variously sized and shaped garments on said form.

17. In a device of the character described, the combination with a garment form comprising relatively slidable wire sections, each of said wire sections having relatively sliding overlapping end portions, and spaced diagonally connected wire clip arms on the ends of said overlapping end portions to frictionally grasp the adjacent overlapping wire portion to relatively guide and retain said wire sections in adjusted relation.

18. In a device of the character described, the combination with a garment form comprising relatively slidable wire sections, each of said wire sections having relatively sliding overlapping end portions, and spaced diagonally connected wire

clip arms on the ends of said overlapping end portions, each of said diagonally connected clip arms being anchored to the end of each overlapping portion to frictionally grasp the other adjacent overlapping wire portion to relatively guide and retain said wire sections in adjusted relation.
